UNITED STATES PATENT OFFICE.

CHARLES GORTON, OF NEW YORK, N. Y.

AGRICULTURAL BOILER.

SPECIFICATION forming part of Letters Patent No. 612,411, dated October 18, 1898.

Application filed November 18, 1897. Serial No. 658,926. (No model.)

To all whom it may concern.

Be it known that I, CHARLES GORTON, of New York, in the county and State of New York, have invented certain new and useful

5 Improvements in Agricultural Boilers; and I do hereby declare that the following is a full, clear, and exact description of the invention, which will enable others skilled in the art to which it appertains to make and use the 10 same, reference being had to the accompanying drawings, and to the letters of reference marked thereon, which form part of this specification.

This invention relates to the class known 15 as "agricultural" boilers, and has for its object economy of space, efficiency in use, cheap in first cost, and simple and durable and readily operated; and to this end my invention consists of a boiler made in sections, prefer- 20 ably semicylindrical in form, each section in this instance having one flat side and so ar- ranged that each flat side faces the other, leaving a space between them, the sections to be connected near their bottoms by suitable 25 smoke and heat flues. Two or more sections may be used, each having flat sides and uniting to make a nearly cylindrical form.

Heretofore agricultural boilers have been made bulky, heavy, and cumbersome, which 30 rendered them difficult to move from place to place about a farm, and frequently the stock had to be driven to where the boiler was located instead of taking the boiler where the stock was, and thus much time and loss 35 ensued. My invention is so constructed that it can be removed from the barrel or tank and conveyed to any part of the field or from one part of the barn-yard to the other and placed in another barrel or tank, thus making it per- 40 fectly portable for use.

In the drawings, Figure 1 represents the feed cooker or boiler partly in section, also showing it located within a barrel ready for use. Fig. 2 shows a plan view of my im- 45 proved boiler within the barrel.

The same letters designate like parts throughout both figures.

A is the barrel, and B the heater, with fire-space therein, in which is located a grate, 50 preferably inclined.

C is the auxiliary heater, connected to heater

B by flue D. This flue D is located near the bottom of the heaters, the heaters and flue being water-tight, so that leakage into them from the barrel is provided against. 55

The top or lid a of heater B is removable and generally detached when fuel is to be supplied to the furnace or fireplace. This lid a is provided with handles for lifting it off, as usual, and also with draft-opening b, 60 which may be of the register pattern and made to control the draft.

The auxiliary heater C is provided with an uptake or chimney d, through which the es- 65 caping smoke and gases pass.

The operation of the apparatus is as fol- 70 lows: A suitable barrel or tank being sup- plied with water, the heater is placed therein until it is submerged. Suitable clamps of any ordinary construction may be used to retain the tank in a submerged condition. The lid 75 is then removed and fire is made upon the grate of any suitable combustible material. When the fire is well under way, the lid or cover is again placed in position and the draft regulated, when it is ready for use. Vegeta- 80 bles—such as corn, turnips, potatoes, or food of any kind suitable for cattle or hogs or other animals—are then placed in the tank or barrel and undergo the process of treatment (cooking) to be fed to said cattle or other animals.

The advantages of cooking food for live 85 stock are admitted by every thoughtful and thorough farmer. The actual saving in food has been proven by experiment by hundreds of farmers, both practical and scientific. To get the best results out of the cooker, it should be entirely submerged; otherwise much heat will be lost by exposing any portion of the 90 heating-surface to the atmosphere.

By making the sections segmental and flat- 95 sided and separating them so that water will come in contact with the said flat side I get a vastly-increased heating-surface without increasing the fuel-space or encroaching upon the space for the food, so that I really have a double heater instead of a single one, and thus almost double the capacity of the cooker, without increasing its bulk or quantity of 100 fuel to be used in cooking a given quantity of food.

I may describe a very important use of the heater without detriment, and that is in very cold and frosty weather my heater can be placed in the trough for watering cattle before they drink, and thus take off the extreme cold from the water, which chills the animals if drank cold at that particular season of the year.

Hundreds of good uses might be set forth for this simple invention, but it is thought that the foregoing is sufficient for the ready understanding of the most ignorant person to make and use it.

It will be understood that many modifications or alterations may be made within the scope of my invention without departing from the spirit thereof.

In this construction the danger from fire is greatly reduced, as the fire in the apparatus is entirely submerged within the tank, and

therefore less liable to ignite with combustible matter around the farm-yard.

What I claim and desire to secure by Letters Patent is—

An agricultural boiler composed of ²⁵ segmental sections connected by flues located at or near the bottom thereof, one of said sections having a fireplace or furnace and the others forming auxiliary heating-chambers, the former being provided with a feeding top ³⁰ or lid, and the latter with uptakes or chimneys, as set forth.

In testimony that I claim the foregoing as my own I affix my signature in presence of two witnesses.

CHARLES GORTON.
